UNITED STATES PATENT OFFICE

150,760

DESIGN FOR A RADIATOR GRILLE AND ENCLOSURE STRUCTURE

Henry Dreyfuss, New York, N. Y., assignor to
Deere Manufacturing Co., a corporation of
Iowa.

Application November 1, 1946, Serial No. 134,459

Term of patent 14 years

(Cl. D14—18)

To all whom it may concern:

Be it known that I, Henry Dreyfuss, a citizen of the United States, residing at New York city, in the county of New York and State of New York, have invented a new, original, and ornamental Design for a Radiator Grille and Enclosure Structure, of which the following is a specification, reference being had to the accompanying drawings, forming a part thereof, in which:

Figure 1 is a perspective view of the front and side of a radiator grille and enclosure structure showing my new design;

Figure 2 is a front perspective view; and

Figure 3 is a plan view.

I claim:

The ornamental design for a radiator grille and enclosure structure, as shown.

HENRY DREYFUSS.
